UNITED STATES PATENT OFFICE.

ALLEN E. BARNETT, OF PRINCETON, MISSOURI.

ATTACHMENT FOR AUTOMOBILE RADIATORS.

Application filed August 11, 1923. Serial No. 656,973.

To all whom it may concern:

Be it known that I, ALLEN E. BARNETT, a citizen of the United States, residing at Princeton, in the county of Mercer and State 5 of Missouri, have invented certain new and useful Improvements in Attachments for Automobile Radiators, of which the following is a specification, reference being had to the accompanying drawings.

10 This invention relates to attachments for automobile radiators and more particularly to a filling cap therefor.

An important object of this invention is to provide a device of this character of such 15 construction that the radiator may be readily filled without spilling water upon the radiator and hood of the engine and which at the same time will present a pleasing appearance.

20 A further object of the invention is to provide in a filling cap a construction such that when the cap is open to permit the insertion of water to the radiator the upper end of the drain pipe of the radiator is 25 closed to prevent water which is being placed in the radiator from passing therethrough to the ground.

These and other objects I attain by the 30 construction shown in the accompanying drawings wherein for the purpose of illustration is shown a preferred embodiment of my invention and wherein:—

Figure 1 is a perspective view showing a 35 filler cap constructed in accordance with my invention in position upon a radiator;

Figure 2 is a transverse sectional view through the cap on the line 2—2 of Figure 3;

Figure 3 is a section on the line 3—3 of 40 Figure 2; and

Figure 4 shows a slightly modified form of construction.

Referring now more particularly to the drawings, the numeral 10 indicates the upper reservoir of a radiator and 11 the filling opening thereof. As is usual, this filling opening is threaded for the reception of a closure cap. My cap consists of a neck 12, 45 threaded for engagement in the filling opening, and a body portion 13 carried by the upper end of this extension.

The body portion 13 of the filler cap is 50 preferably circular or substantially circular in cross section. When circular in cross section the head will be positioned upon the neck 12, as indicated in Figure 4. Where

the head or body portion 13 is positioned centrally upon the neck the rear face thereof must be flattened, as indicated at 14, to admit passage of the hood cover of the machine when removing or applying the same. The head 13 is transversely elongated, being elliptical in form when viewed in plan or front elevation. This head is hollow and is formed in two sections 15 and 16, comprising 55 a base which is substantially three-quarters elliptical, the opening being arranged at the upper forward side thereof and extending across the entire length, the cap 16 completing the structure and closing the 60 opening. This cap is hinged at its upper edge to the base, as indicated at 17, and is provided at its lower edge with a catch 18 by means of which it is held in closed position. Particular attention is directed to the 65 positioning of the opening of the base formed by swinging the cap 16. It will be noted that this opening, since it extends the full length of the head, is relatively broad and accordingly will accommodate a bucket 70 or other implement employed in transferring water to the radiator. It will further be noted that the rear of the opening is provided with an upstanding wall or flange 75 preventing water from being splashed on the hood 15. In fact the head, when broadly considered, consists of a trough having at its rear edge a flange and a cap pivoted to this flange for closing the trough.

As is well known to those familiar with 80 the art, practically all automobile radiators are provided with an overflow pipe 19 for limiting the high level of water in the radiator. The open mouth of this overflow pipe usually projects into the lower end of 85 the neck 20 in which the filling opening 11 is formed. Accordingly when water is delivered to the filling opening a portion of this water ordinarily enters the open upper end of the overflow pipe and passes 90 therethrough to the ground, often splashing upon the legs of the person who is filling the radiator. In order to prevent this waste of water I pivot in the base 95 15, as at 21, a lever 22 which extends 100 transversely of the base and has one end positioned immediately above the open upper end of the filler pipe 19. To this end, as at 23, is pivoted a stem, the lower end 105 of which extends into the filler pipe. Secured to this stem is a washer or valve 24, which when the lever is relieved rests upon

and closes the upper end of the filler pipe. The opposite end of the lever extends adjacent the end 25 of the base and when the lever is relieved projects above the edge 5 of the opening of the base. The lid 16 bears a trip member 26, which during closure of the lid engages the end 25 of the lever to depress the same and thereby elevate the opposite end of the lever with the stem 10 23 to lift the valve 24 from the upper end of the overflow pipe 19 and thereby permit the overflow pipe to function in the usual manner.

I have additionally discovered that with 15 the use of such extension filling necks there is a tendency to trap air in the lower end of the neck 20 of the reservoir, with the result that the water in entering the radiator gurgles and has a tendency to splash 20 as the air passes upwardly therethrough. In order to prevent this I provide a vent pipe 27 having its lower end positioned adjacent the lower end of the neck 20 of the radiator 10 and its upper end opening 25 through the upper end or flange of the base portion, as indicated at 28. Through this vent pipe trapped air may pass permitting the water to pass smoothly into the radiator and preventing such splashing. It will 30 be seen that the features hereinbefore set forth combine to provide a radiator and filling cap which is simple in its construction and arrangement but which assists materially in filling the radiator in that it 35 prevents splashing and loss of the water and permits the use of larger mouthed vessels for transporting the water than heretofore

practical. It will furthermore be obvious that the construction hereinbefore set forth is capable of some change and modification 40 without in any manner departing from the spirit of my invention and I accordingly do not limit myself to such specific structure except as hereinafter claimed.

I claim:—

1. The combination with a radiator reservoir having a filling neck and an overflow pipe for the reservoir having its upper end extending into the filling neck, of a filling cap engaged with the filling neck 50 having a funnel body, a closure cap for the funnel body, a valve normally closing the upper end of the vent pipe, and means operated by the closing of the closure cap for opening said valve.

2. The combination with a radiator reservoir having a filling neck and an overflow pipe for the reservoir having its upper end extending into the filling neck, of a filling cap engaged with the filling neck 60 having a funnel body, a closure cap for the funnel body, a valve normally closing the upper end of the vent pipe, means operated by the closing of the closure cap for opening said valve, including a lever pivoted intermediate its end within said funnel body and having one end extending over and secured to said valve, and means carried by said cap for engaging the opposite end of the lever.

In testimony whereof I hereto affix my signature.

ALLEN E. BARNETT.
